DESIGN FOR A PORTABLE MAGAZINE RACK

William Hansen, Chicago, Ill.

Application October 4, 1946, Serial No. 133,741

Term of patent 7 years

(Cl. D33—2)

To all whom it may concern:

Be it known that I, William Hansen, a citizen of the United States and a resident of Chicago, in the county of Cook and State of Illinois, have invented a new, original, and ornamental Design for a Portable Magazine Rack, of which the following is a specification, reference being had to the accompanying drawings, forming a part thereof.

In the drawings:

Figure 1 is a perspective view of a portable magazine rack showing my new design;

Fig. 2 is an end elevation of the rack; and

Fig. 3 is a top plan view of the rack.

I claim:

The ornamental design for a portable magazine rack, substantially as shown.

WILLIAM HANSEN.
